UNITED STATES PATENT OFFICE.

LOUIS W. DOWNES, OF PROVIDENCE, RHODE ISLAND.

METHOD OF AND APPARATUS FOR INSULATING ELECTRICAL CONDUCTORS.

SPECIFICATION forming part of Letters Patent No. 534,785, dated February 26, 1895.

Application filed August 22, 1894. Serial No. 521,029. (No model.)

To all whom it may concern:

Be it known that I, LOUIS W. DOWNES, of Providence, Rhode Island, have invented a new and useful Improvement in Methods of 5 and Apparatus for Insulating Electrical Conductors, which is fully set forth in the following specification.

The present invention relates to a method of and apparatus for applying an insulating 10 covering to electrical conductors. The said method and apparatus are specially designed for the production of an electrical conductor with an insulation composed of asbestos, and the insulated conductor produced by the new 15 method and apparatus is included in the invention.

Heretofore, asbestos insulation has been defective and unsuitable for a great variety 20 of uses in the electrical art because, from the nature of the substance, it is extremely difficult to apply it to the wire in a compact, uniform and sufficiently thin coating, and in a permanent manner. The expense and bulkiness of conductors covered partly or entirely 25 by asbestos have also stood in the way of their use.

It has been proposed heretofore to apply 30 an asbestos covering to a tube by weaving or braiding (as in a whip-braiding machine) strands of asbestos fiber around a wire, but such procedure has not been found successful 35 in practice because the asbestos fibers are short and brittle, and the covering is easily abraded, and detached from the wire in handling and use. For these and like reasons asbestos-insulated wire has not up to the present time become an article of manufacture. The object of the present invention is to remove 40 these difficulties, and to provide means for the manufacture of asbestos insulated conductors at small cost and having the properties requisite to admit of their use in armature windings, house-wiring, and for like purposes.

According to my present invention the wire 45 after first being coated with a quick drying adhesive mixture, such as some form of gum, applied thereto by any suitable means, is covered with the asbestos fiber, wound spirally 50 or otherwise thereon, by any suitable mechanism well known to those familiar with the art. The wire is then subjected to a finish-

ing process consisting in, first, combing or brushing out the asbestos covering to remove all superfluous lumps, irregularities, &c., and 55 laying the nap all in one direction; second, applying pressure to the covering whereby the fiber is matted together in a compact layer, the thickness being gradually reduced to a suitable point; third, applying a coating 60 of a water-proofing and toughening compound, to protect the insulation from injury in handling, and to impart to it moisture-resisting properties. After these operations the conductor is preferably passed again between pressure rolls and drawn through dies 65 to impart a smooth finish and reduce the insulated conductor to an even diameter.

The brushing or carding of the asbestos fiber is an important step of the process and 70 contributes largely to the excellence of the finished product, and it is mainly to admit of this operation being successfully performed that the wire is coated with adhesive substance before applying the asbestos fiber, 75 since I have found it impracticable to raise the nap properly unless the fiber is applied to the wire by the aid of an adhesive material. I therefore desire to cover broadly the improvement consisting in applying the fiber 80 by means of an adhesive substance and brushing, carding or raising the nap, irrespective of the precise mode adopted for finishing the product.

In order that the invention and the best 85 means now known to me of applying the same in practice, may be fully understood, I will describe the same in detail with the aid of the accompanying drawings, in which—

Figure 1 is a plan view of apparatus employed in carrying out the process, and which is also included in the invention. Fig. 2 is a side elevation thereof. Fig. 3 is a detail view in side elevation of the carding or brushing devices. Fig. 4 is an end elevation thereof. Fig. 5 is an end elevation of one set of pressure-rolls. Fig. 6 is a detail in vertical section of the 90 rollers and their actuating mechanism. Figs. 7 and 8 are detail views representing the conductor on an enlarged scale.

In the drawings *a* represents the conductor having a covering of asbestos fiber applied and held thereon by means of a quick-drying adhesive gum, as already described. Inas-

much as there are appliances in common use for wrapping wires with fibrous material, any of which may be used for the purposes of this process, it is not necessary to give a description 5 of such appliances.

All the moving parts of the machine are driven from a main shaft A through suitable gearing, as clearly shown in the drawings.

The covered wire is subjected to the action 10 of the carding or brushing devices (Figs. 1 and 3). These devices comprise a suitable brush or brushes b carried by a disk B, the brush-holder b' being adjustable radially of said disk by means of a screw b². Disk B receives 15 motion from shaft A through a spur gear C on said shaft, and a pinion c attached to the disk. The pinion, its hub and the disk are all provided with a central passage through which the wire passes. To disk B is also secured 20 a bracket c' upon which the wire rests while under the action of brush b; and as the latter rotates the nap is raised and laid all in the same direction, while all lumps and inequalities in the fiber are removed, bringing 25 the covered conductor more nearly to a uniform diameter. After passing through a guide D' the wire is subjected to the action of a series of pressure rolls. In the machine shown there are two sets of these rolls (designated 30 E and F in Figs. 1 and 2) but there may be more or less as desired. The particular construction of these devices is illustrated in Figs. 5 and 6. The disk E' is mounted on the hub of a pinion e which receives motion from 35 a spur gear G on the main shaft. To the face of this disk are secured three radial slides f set one hundred and twenty degrees apart and adjustable radially by means of set screws f'. Each slide carries at its inner end a small 40 roll g the shafts g' of these rolls being parallel with the line of travel of the wire a. The pressure of the rolls being properly regulated by the set screws, they compress and mat the asbestos fiber, reducing gradually the thickness 45 of the insulated conductor to a suitable point.

D² D³ indicate other guides through which the wire passes, and H indicates a take-up roll around which the wire is led, and which draws 50 it through the napping and rolling devices. This take-up roll is driven from a worm h through pinions h' h². The wire then passes between two rolls k l by means of which the toughening and water-proofing compound is 55 applied. For this purpose I may use with advantage any suitable oil having the desired properties such as linseed. Rolls k l are faced with felt or other absorbent substance, and the latter dips into a small tank I containing 60 the oil or water proof liquid, roll k taking a sufficient supply thereof by contact with roll l.

M, N represent two sets of finishing rolls, the axes of the two sets being at right angles to each other. These rolls are simply to 65 smooth down the coating and remove the excess of oil. Finally it is passed through a

guide D⁴, which may be a die, to give it a final smooth finish, and is wound on a spool or reel P, which is rotated from the main shaft through bevel gears p, p', pulley q, belt 70 q' and pulley q², the latter being on the shaft of the reel.

Fig. 7 illustrates on an enlarged scale the appearance of the conductor a after the first operation of winding the asbestos strand or 75 thread x thereon. The turns of thread are laid as close together as possible, but at this stage each spiral is, of course, separate from the others. They present numerous lumps 80 and inequalities, and their hold upon the wire and upon one another is very slight.

Fig. 8 illustrates the finished product, in which the separate spirals disappear, the covering resembling a continuous and coherent 85 fabric, dense and smooth and adhering with considerable tenacity to the wire.

Obviously many variations may be introduced in the manner of finishing the product after raising the nap in the manner described, and in the character of the appliances used 90 for performing the several steps of the process. It is also obvious that some of the steps of the process and parts of the described apparatus may be used without others.

The finished product has physical characteristics which distinguish it from other insulated conductors heretofore made or known. The covering is dense and compact, the fibers being well matted or felted together and adhering closely to the wire. The surface is 100 smooth and uniform and the covering very thin. I find that an effectual insulation can be produced of a thickness less than 0.01 of an inch, which is of great importance in windings for armatures and field coils. These 105 qualities of the finished product are due to the napping and compressing of the fiber, producing an extremely tough, dense and coherent fabric, as distinguished from a series of coils with more or less space between them, 110 and with an inherent tendency to separate. In point of economy the conductor compares favorably with that insulated by a braided cotton covering in common use.

Having thus described my invention, what 115 I claim is—

1. The described process of applying a fibrous insulating covering, such as asbestos, to an electrical conductor, which process consists in coating the conductor with an adhesive substance, wrapping or winding the fiber thereon, brushing or carding the latter to raise a nap and then pressing or compacting the fiber, substantially as set forth.

2. In the manufacture of insulated electrical conductors, the improvement which consists in applying a fibrous covering of asbestos to the wire, brushing the fiber in one direction, and compressing and reducing it to a smooth surface and uniform diameter, substantially as described.

3. In the manufacture of insulated electri-

cal conductors, the improvement which consists in coating a wire with adhesive substance, wrapping it with fibrous asbestos, brushing out the nap in one direction, rolling 5 the fibrous covering upon the wire, and then applying thereto a water-proofing substance substantially as described.

4. The described process of manufacturing insulated electrical conductors, which process 10 consists in coating a wire with adhesive substance, wrapping it with fibrous asbestos, brushing the fibrous coating to raise the nap, compressing it between pressure rolls, coating 15 with waterproof material, and subjecting it to a final rolling to produce a smooth finished surface, as set forth.

5. In an apparatus for the purpose specified, the combination of devices for feeding a wire longitudinally, a rotating brush or card- 20 ing device having its axis of rotation coincident with the axis of the wire, pressure-rolls for compressing the nap raised by the brush, and rolls for applying a water-proofing substance, substantially as described.

25 6. The combination with the wire-feeding mechanism, of a rotating brush for acting on the surface of the wire as it advances, pressure rolls having their axes parallel with the wire, and mechanism for rotating the rolls

circumferentially about the same as it is fed 30 forward, substantially as described.

7. The combination with the wire-feeding mechanism, of a rotating brush, pressure rolls having their axis parallel with the wire, means for turning the rolls circumferentially 35 around the wire, means for applying to the surface of the wire a water-proofing compound, and finishing pressure rolls, all arranged and operating substantially as described. 40

8. As an article of manufacture, an electrical conductor having a compact, uniform covering of asbestos fiber, wound spirally thereon, matted compressed and water-proofed substantially as described. 45

9. As an article of manufacture, an electrical conductor having a thin, compact, uniform covering of asbestos fiber wound thereon and attached by adhesive substance, the fibers being matted and compressed into a coherent 50 fabric, substantially as described.

In testimony whereof I have signed this specification in the presence of two subscribing witnesses.

LOUIS W. DOWNES.
